SHALE DISTILLATION WITH FLUIDIZED RESIDUE TREATMENT

Harold V. Atwell, Beacon, N. Y., assignor to The Texas Company, New York, N. Y., a corporation of Delaware

Application May 29, 1946, Serial No. 673,141

3 Claims. (Cl. 202—15)

1

This invention relates to the distillation of oil shales for the recovery of volatilizable constituents therefrom.

In accordance with the invention a solid, comminuted or powdered material is heated to a high temperature by being contacted with combustion gases, the highly heated comminuted or powdered material is brought into contact with, and fluidized in, a gaseous medium to obtain heat transfer to the gaseous medium and the heated gaseous medium is directed into contact with the shale to effect the distillation thereof.

In the distillation of oil shale more or less disintegration takes place so as to produce quantities of pulverulent or comminuted material and in accordance with the invention this pulverized or comminuted material may be removed from the distilling zone before complete removal of its hydrocarbon or carbonaceous content and this material is fluidized and subjected to combustion to thereby impart a high degree of heat to the material. The heated material is then fluidized with gas, preferably a hydrocarbon gas, and the resultant heated gas is delivered to the retort to effect destructive distillation of the shale.

The accompanying drawing is a flow diagram illustrating a preferred embodiment of the invention.

Referring to the drawing, comminuted or powdered solid material is contained in a hopper or feeding means 10. This comminuted material preferably includes finely divided or powdered shale recovered from the distillation of the raw shale and which contains some hydrocarbon or carbonaceous content not removed in the distillation. Makeup comminuted material from an extraneous source may be included in the material contained in the hopper. A fluidizing medium is directed through line 11 and serves to withdraw comminuted material from the hopper 10 and fluidize it. The fluidizing medium may be air or oxygen-containing gas or inert gas. Preferably fuel gas such as recycle gas recovered in the process is used as the fluidizing medium. The comminuted material is transported in suspension in the fluid medium through line 11 thence through lines 12 and 13 to a combustion chamber 14. When air or oxygen-containing gas is not used as the fluidizing medium, which will generally be the case in order to avoid combustion in the transporting lines, air or oxygen-containing gas is introduced directly to the combustion chamber through line 12A. In the combustion chamber the carbonaceous material contained on the comminuted solid mate-

2

rial is burned under fluidized conditions. In cases where the quantity of carbonaceous material on the spent shale and the quantity of fuel gas used in fluidizing and transporting the comminuted solid material is insufficient to obtain the extent of combustion desired, auxiliary fuel gas may be introduced through a line 15.

The upper portion of the combustion chamber 14 may be of increased diameter to provide a separating zone 14A for separating the combustion gases from the powdered material. The separated gases flow out through a flue 19. Cyclone separators may be used in lieu of the separating zone 14A, or in addition thereto, to assure complete separation.

The comminuted material collects in a section 17 shielded from the flow of gases. The material is withdrawn through a standpipe 18 to which may be connected one or more pipes such as 19 for introducing small quantities of gas to prevent the comminuted material from packing in the standpipe and to maintain it in a more or less aerated condition.

A gaseous medium such as hydrocarbon gas (recycle hydrocarbon gas) or steam or a mixture thereof directed through line 20 serves to aspirate comminuted solid material delivered from the standpipe 18 and to fluidize it. The gas may advantageously be preheated, prior to contacting with the hot solid material from the combustion zone, by heat exchange with the flue gases. The mixture is delivered to a chamber 21 wherein the comminuted material and the gaseous medium are in contact under fluidized conditions. The comminuted material and gaseous medium are maintained in a dense phase and in a turbulent condition in the lower sections of the chamber 21 which conditions are conductive to maximum transfer of heat from the comminuted material to the gas. The upper portion of the chamber 21 may be of increased diameter to provide a separating zone 22 for separating the comminuted material from the gas.

The comminuted material collects in a section 23 shielded from the flow of gases and is withdrawn through a standpipe 24 to which may be connected one or more pipes such as 25 for introducing small quantities of gas to maintain the material in the standpipe in an aerated condition. A fluidizing gas, such as air or recycle hydrocarbon gas, introduced through line 12 functions to withdraw the comminuted material from the standpipe 24 and recycle it to the combustion chamber 14. When it is not desired to recycle the comminuted material it is withdrawn

through a line 26. In some cases only a portion of the comminuted material is recycled and the excess is withdrawn through the line 26.

The separated gas is withdrawn from the separating section 22 of the chamber 21 through a line 27 and is delivered to a distilling retort 28 for distilling the shale. Lump shale is charged through a screw conveyor 29 to the upper end of the retort 28. The hot gaseous medium is preferably introduced to the lower portion of the retort 28 as shown so as to thus provide countercurrent contacting of the hot gas with the lump shale. The volatilized products are removed through a vapor line 31 and conducted to suitable fractionating equipment (not shown) to recover the desired products.

The shale from which substantially all or at least the bulk of the volatilizable material has been distilled off is withdrawn through the bottom of the retort and may be removed by means of a screw conveyor 30.

The removal of the volatilizable constituents or the greater portion thereof from the lump shale will normally effect more or less disintegration of the lumps so that portions of the material discharged from the retort will be in a sufficiently comminuted form to be fluidized with a gaseous or vaporous medium. In such cases this comminuted material, after screening when necessary, may be directed to the hopper 10 for fluidizing in the line 11 and delivery to the combustion chamber 14. Fragments that are too large for fluidizing may be discarded or they may readily be ground to a proper size since the residual product from the distillation is normally in a friable condition and much more easily pulverized than the raw shale before distillation. Frequently a certain amount of shale dust will pass out from the retort through the vapor line and by inserting a cyclone separator in the line the dust may be separated and directed to the hopper 10.

Oil shales vary considerably in characteristics but generally speaking hydrocarbon gases are evolved at initial temperatures around 650-750° F., oil vapors and gases are freely given off at temperatures around the 900° F. level and as a rule all the recoverable vapors will be removed at a temperature approximating 1000° F. or at somewhat lower temperatures. Ammonia gas begins to come off at about 555° F. and may continue more or less through the distillation. In practicing the invention the fluidized comminuted material is subjected to combustion temperatures of about 2000 to 2500° F. in the combustion zone. The temperature of combustion should be kept below the melting point of the ash or solid material. The highly heated comminuted material upon being fluidized with the gaseous medium, preferably recycle hydrocarbon gases, imparts heat to the gaseous medium which is then delivered to the shale retort at temperatures approximating 1500° F. With the entering gas at this temperature an effective distilling zone at temperatures of about 900-1000° F. is maintained in the lower sections of the retort to thereby effect destructive distillation of the shale. The evolved vapors and gases are subjected to fractionation to recover the hydrocarbon oils and gases. When recycling hydrocarbon gas the gas is advantageously preheated in an exchanger receiving heat from the combustion gases leaving the combustion chamber prior to being used to fluidize the hot comminuted material which is withdrawn from the combustion chamber. It is advantageous to withdraw the residual shale from

the retort before complete volatilization of carbonaceous material so that a certain amount of the carbonaceous or hydrocarbon content of the shale may remain with the withdrawn residual shale. The combustion of this carbonaceous or hydrocarbon material in the combustion zone serves to provide the necessary heat for heating the comminuted solid material therein. Fuel gas introduced into the combustion chamber, preferably recycle gas, provides such additional heating as may be required.

Although a preferred embodiment of the invention has been described herein, it will be understood that various changes and modifications may be made therein, while securing to a greater or less extent some or all of the benefits of the invention, without departing from the spirit and scope thereof.

I claim:

1. The method of distilling oil shales that comprises charging lump shale to a distilling zone, introducing gas heated as hereinafter specified to the distilling zone to effect destructive distillation of the shale and produce resultant disintegration thereof with formation of comminuted residual shale, withdrawing comminuted residual shale containing carbonaceous material from the distilling zone and fluidizing it in a fluidizing medium, transporting the comminuted residual shale in suspension in the fluidizing medium to a combustion zone, subjecting the fluidized comminuted residual shale therein to combustion under fluidized conditions, separately withdrawing resultant highly heated comminuted burned shale from the combustion zone, fluidizing it with gas and passing the fluidized stream into a zone wherein the gas and comminuted shale are in contact in dense phase and turbulent conditions to effect rapid transfer of heat from the shale particles to the gas, separately withdrawing resultant heated gases and comminuted material from said zone and introducing the separated gas into the distilling zone to effect the destructive distillation of the lump shale as aforesaid.

2. The method of distilling oil shales that comprises charging lump shale to a distilling zone, introducing gas heated as hereinafter specified to the distilling zone to effect destructive distillation of the shale and produce resultant disintegration thereof with formation of comminuted residual shale, withdrawing residual shale containing carbonaceous material from the distilling zone, obtaining comminuted residual shale from the residual shale so withdrawn and fluidizing it in a fluidizing medium, transporting the comminuted residual shale in suspension in the fluidizing medium to a combustion zone, subjecting the fluidized comminuted residual shale therein to combustion under fluidized conditions, separately withdrawing resultant highly heated comminuted burned shale from the combustion zone, fluidizing it with gas and passing the fluidized stream into a zone wherein the gas and comminuted shale are in contact in dense phase and turbulent conditions to effect rapid transfer of heat from the shale particles to the gas, separately withdrawing resultant heated gases and comminuted material from said zone and introducing the separated gas into the distilling zone to effect the destructive distillation of the lump shale as aforesaid.

3. The method of distilling oil shales that comprises charging lump shale to a distilling zone, introducing gas heated as hereinafter specified

to the distilling zone to effect destructive distillation of the shale and produce resultant disintegration thereof with formation of comminuted residual shale, withdrawing residual shale containing carbonaceous material from the distilling zone, separating comminuted residual shale from the residual shale so withdrawn and fluidizing it in a fluidizing medium, transporting the comminuted residual shale in suspension in the fluidizing medium to a combustion zone, 10 subjecting the fluidized comminuted residual shale therein to combustion under fluidized conditions, separately withdrawing resultant highly heated comminuted burned shale from the combustion zone, fluidizing it with gas and passing the fluidized stream into a zone wherein the gas and comminuted shale are in contact in dense phase and turbulent conditions to effect rapid transfer of heat from the shale particles to the gas, separately withdrawing resultant heated 15 gases and comminuted material from said zone 20

and introducing the separated gas into the distilling zone to effect the destructive distillation of the lump shale as aforesaid.
